UNITED STATES PATENT OFFICE.

FRANK W. BROOKE, OF PITTSBURGH, PENNSYLVANIA.

BAR-HEATING FURNACE.

Application filed May 8, 1926. Serial No. 107,647.

It is the object of the invention to provide a furnace for heating bars, slabs or billets for rolling, in which the pieces will be evenly heated, and the pieces can be charged and discharged with minimum manual labor.

In the accompanying drawings, Figure 1 is a central sectional elevation of a heating furnace showing one embodiment of the invention, Figure 2 is a sectional plan view 10 on the line II--II of Figure 1, and Figure 3 is a detached plan view of a supplemental detail.

The furnace may be any well known or 15 suitable type of continuous heating furnace, such for instance as that shown in Letters Patent No. 632,020, in which the pieces being heated are pushed in contiguous succession upon a track extending through the heating-chamber. I have shown in the drawings, 20 however, a furnace intended for the pair-heating of sheet-bars, which are slabs of iron or steel having a thickness less than the respective dimensions of their opposite flat 25 surfaces, and which rest on edge on the track in their passage through the heating-chamber. This furnace, as shown in the drawings, is provided with a combustion-chamber 1 for heating by means of coal, using a 30 standard form of stoker, the flame and products of combustion flowing over the bridge-wall 2 into the heating-chamber 3, and thence through the heating-chamber and out 35 through the flues 4, 4, at the opposite or rear end of the heating-chamber, and into the stack-flue 5. But the character of fuel employed and the manner of its introduction into the heating-chamber are not material to the invention.

The bars or billets being heated are caused 40 to pass through the heating-chamber 3 on ways which are elevated above the floor 6 of the chamber, with the space beneath the ways in open communication with the body of the 45 chamber. These ways preferably consist of hollow water-cooled skid-pipes 7 of well known form which are laid in the top surfaces of pedestals 9 arranged at intervals in rows longitudinally of the chamber. Thus a 50 pair of the longitudinal skid-pipes 7 constitutes a track through the chamber for the bars or billets.

In the heating-chamber the space 13 underneath the bars on the track is in open communication with the body of the heating-chamber through the openings 14 between

the pedestals 9. In order to draw active currents of the heated products of combustion around and underneath the bars, flue-ports 15 are formed in the floor 6 of the chamber 60 beneath the track and are connected to a flue 16 underneath the floor, the latter opening into the stack-flue 5. Thus not only is there always maintained the main current of the 65 products of combustion above the bars from the front to the rear of the heating chamber, but commencing at the front of the chamber and throughout its length active currents of 70 high heat intensity are caused to flow down around and beneath the bars, thus subjecting 75 the bars equally on all exposed surfaces, and throughout their travel, to immersion in an active homogeneous bath of heat of substantially equal intensity in any given cross-sectional zone taken transversely of the heating-chamber. The bars are thus effectively heated with the maximum uniformity attainable in furnaces of this type.

The charging-opening 20 of the furnace is formed in the front end-wall 21 and is 80 provided with a vertically sliding door 22. The reciprocable pusher-head 23 may be operated by any suitable means, various types of which are well known. In this case the head is shown as connected at its opposite 85 ends to the threaded rods 24, which are reciprocated through suitable connections with the armature-shaft of the motor 25.

For retaining the row of bars in place 90 in the heating-chamber and preventing them from falling backwardly there is provided a suitable latch or support which is preferably automatic in operation. The preferred latch comprises a head 38 mounted on the outer end of the bent arm 39, which projects inwardly and is pivoted medially at 95 40 underneath the heating-chamber. A weight 41 is carried on the inner end of the arm, and the head 38 works through a slot or recess 42 in the sole-plate 43. The inner face of the head 38 is shaped to support the bars in upright or other desired position, and its body portion slopes outwardly and downwardly in an inclined outer face 44. When the bars are pushed into the furnace the head 38 is caused to move downwardly and outwardly on the pivot 40 as a center and below the face of the sole-plates 43, and it is held down until the outermost 100 bar has passed the apex of the inclined face 44. Then as the pusher-head 23 is withdrawn, the weight 41 causes the upward and 105 110

inward movement of the bar-supporting head 38 into supporting contact with the rear face of the outermost bar, thus holding the entire row of bars from falling backwardly.

The lower edge of the door 22 has a slot 45 of suitable form to fit the head 38, so that the front opening 20 of the furnace may be kept entirely closed except only during the 10 charging of the bars.

The skid-track 7 terminates at the point 50 within the heating-chamber, and an inclined track or chute 51 extends downwardly and outwardly from the point 50 to the 15 discharge-opening 52, which is provided with a swinging door 53. The inclined track 51 may consist in whole or in part of bent extensions 54 of the skid-pipes 7; but preferably, as shown, such bent extensions terminate at an intermediate platform 55. In combination with the platform 55 there are arranged at its opposite ends channeled wheels or discs 56, mounted on a shaft 57. The channels 58 formed in the peripheries 20 of the discs 56 are in alignment the one with the other, and are of a width sufficient to span the opposite ends of the bars resting on the platform 55. The forward walls 59 of the opposite channels 58, when in the 25 position shown in Figure 2 of the drawings, act as aligning stops or abutments for the edges of the bars as they slide down upon the platform 55, and the rear walls 60 of the channels act as dogs on the rotation of the discs 56 to push the bars off the 30 platform, whence they slide down the lower portion of the inclined track or chute 51 and out through the discharge-opening. The shaft 57 is turned intermittently, as by the 35 motor 61, to bring opposite channels 58 into position to receive the bars.

Above the apex of the incline 51 at the terminal 50 of the track 7, there is an abutment 62, in the path of the upper portions 45 of the successive bars, so that as a bar comes to the apex of the incline, its lower edge will be tilted outwardly, and thus the bar will slide down the incline with its lower edge in advance, and, as shown in the drawings, the 50 edges of the successive bars or pairs of bars, at their opposite ends, will be stopped by the abutments 59, and the bars can be piled evenly one upon the other on the platform 55. The abutment 62 has supporting-arms 55 63 projecting through the wall of the furnace, having water-passages therethrough for cooling the abutment, and inlet and outlet pipes 64, 65.

The operation is apparent from the foregoing description. The bars are pushed through the heating chamber, in contiguous succession and step by step, by successive feeding operations of the head 23, and after the chamber has been filled, each feeding 60 movement of the head 23 will project one or

more of the heated bars, as may be desired, over the apex of the incline 51, the lower edges of the bars thus discharged being tilted outwardly by the abutment 62, and the bars being properly aligned upon the platform 55 70 by contact of their edges with the abutments 59, and then by turning the shaft 57 the abutments 60 will push the bars off the platform, whence they will slide down the lower portion of the incline 51 and out of the furnace. 75

In Figure 3 there is shown one of a number of extension members for the head 23, to be used for the purpose of emptying all of the bars from the heating-chamber in case 80 of a shut-down of the rolling-mill, or other interruption of the operation. For that purpose the head 23 may be provided with slots at its opposite ends for the reception of extension bars 66, which are connected, as 85 by slots and pins 67, with the supplemental head 68. In the same way additional bars and supplemental heads may be provided. Therefore in the case of an interruption of the operation of the mill, if it is desired to 90 empty the heating-chamber of the furnace, and thus avoid scaling or other injury of the bars, the supplemental head 68 may be connected to the head 23 as described, and upon the latter having reached the limit of its 95 traverse, another pair of bars or a second head and pair of bars may be interposed between the ends of the bars 67 and the head 23, and thus by means of the introduction of these extensions the charging mechanism 100 may be operated to push the entire row of bars out of the heating chamber.

Of course it will be understood that the controlling mechanism for the motors 25 and 61 may be placed at one point, so as to be 105 operated by a single attendant.

I claim as my invention:

1. A bar-heating furnace having a heating-chamber, and a supporting-track for the bars arranged in said chamber, in combination with means arranged at one end of said track for impelling successive bars upon and over said track, and an abutment arranged at the opposite end of said track in the path of the travel of the upper portions of the 115 bars.

2. A bar-heating furnace having a heating-chamber, and a supporting track for the bars arranged in said chamber, in combination with means arranged at one end of said track for impelling successive bars upon and over said track, a downwardly inclined discharge at the opposite end of said track, and an abutment arranged above the apex of said incline in the path of the travel of the upper 125 portions of the bars.

3. A bar-heating furnace having a heating-chamber, and a supporting-track for the bars arranged in said chamber, in combination with means arranged at one end of said 130

track for impelling successive bars upon and over said track, a downwardly inclined discharge at the opposite end of the track, movable bar-receiving means arranged at a me-
dial point in said inclined discharge, and means for moving said bar-receiving means into and away from the path of the bars over the inclined discharge.

4. A bar-heating furnace having a heating-chamber, and a supporting-track for the bars arranged in said chamber, in combination with means arranged at one end of said

track for impelling bars upon and over said track, a downwardly inclined discharge at the opposite end of the track, an intermediate platform in said inclined discharge, movable bar-receiving and aligning means, and means for moving the same first into co-operative relation with said platform to receive and align the bars and then to discharge the bars from said platform.

In testimony whereof I have hereunto set my hand.

FRANK W. BROOKE.
